INTERMEDIATE BUFFER FOR TENDER
LOCOMOTIVES

Robert Gerson da Costa, New Delhi, India

Application December 28, 1949, Serial No. 135,321
In India January 5, 1949

1 Claim. (CL. 213—9)

1

This invention relates to intermediate buffers of the type commonly employed on railway locomotives with tenders to assist in taking buffering loads between the engine and the tender. It is usual to apply a spring load between the engine and the tender up to about 85% of the nominal tractive effort of the locomotive to resist the shuttling vibrations brought about by the inertia of the unbalanced portion of the reciprocating masses and by torque variations.

Several designs of buffers are known for this purpose. In some designs two side buffers are employed and in others a central buffer with friction blocks is interposed between the engine and the tender either above or below the intermediate drawbar.

These designs are generally not free from defects, e. g. the former type tends to resist the free curving of the locomotive and generally does not provide adequate spring loads for resisting fully the shuttling forces that may occur. The latter type, on the other hand, suffers from defects giving rise to pitching vibrations and undesirable frame stresses. In prior art buffers of the central type having friction blocks, the buffering action is applied in a plane generally remote from the plane of the coupled wheel centers in which the shuttling forces actually occur. The result of the difference in the level of the planes in question is that pitching vibrations of considerable magnitude may occur on the locomotive. Furthermore, with the bearing faces, generally not being lubricated, the relative movement between the engine and the tender is resisted by high friction forces which, applied as they are to the back of the locomotive, cause excessive lateral loads to occur at the guiding wheels in the leading part of the locomotive. Further, such high friction forces overstress the engine and the tender frames and occasionally lead to breakage of parts.

The object of the present invention, therefore, is to propose an intermediate buffer for tender locomotives which would eliminate the above-mentioned defects. The important purpose served by the present invention is that it does not allow the pitching vibrations to become excessive on the locomotives. It also avoids the overstressing of the drawbar as a result of the shuttling action between the engine and the tender.

According to the present invention, the contact surfaces of the buffer head on the tender and the bearing block on the engine, are lubricated so as to reduce the friction forces and thereby minimize the lateral reactions between

2

the engine and the tender which are generally pronounced when going over curves and turnouts.

According to the present invention, the intermediate buffer consists of a cast iron or steel buffer head, placed concentrically with the drawbar, the latter passing through a specially designed aperture in the buffer head casting. The arrangement enables the drawbar and the buffer head to be located very much closer to the plane of the coupled wheel centers, thereby considerably reducing the pitching of the locomotive. The buffer head is provided with a radiused surface fitted with a hardened steel liner, which bears against a hardened rubbing block. The contact surfaces are suitably lubricated to reduce friction and to minimize the lateral reactions on the trailing end of the locomotive or on the leading end of the tender. The wear on the contact surfaces is also kept to a minimum, thus maintaining the spring load at a figure close to its designed value.

The arrangement according to the present invention is suitable for the application of any designed spring load and there is no difficulty in applying a load up to 1 and $\frac{1}{2}$ times the nominal tractive effort of the locomotive, if necessary. The buffer itself offers the minimum resistance in the curving of the locomotive and is self-aligning.

The invention will now be described with respect to the accompanying drawings which show details of the components. Like reference numerals have been used to indicate the same components in the various figures.

Figure 1 is a plan view of the buffer head fitted with the manganese steel wear liner and loaded with springs;

Figure 2 is a view in elevation showing the buffer head together with the lugs which support it, the lugs being fitted with the metallic wear liners of hard-wearing quality;

Figure 3 is a view in section taken on the line 3—3 of Figure 1, the interdrawbar being removed for convenience of illustration;

Figure 4 is a view in elevation of the bearing block on the engine showing the lubrication arrangement;

Figure 5 is a plan view of a modified form of buffer head and shows the manganese steel wear liner as well as one of the loading springs;

Figure 6 is a sectional view of the buffer head of Figure 5 taken along the central horizontal line 6—6 of Figure 5;

Figure 7 is the end view of the buffer head of Figure 5;

Figure 8 is the enlarged side view of one of the

lugs which form an integral part of the tender drag box;

Figure 9 is the plan view of the wear liner on the lug shown in Figure 8; and

Figure 10 shows the end view of the bearing block on the engine which coacts with the Figure 5 buffer head.

Referring first to Figures 1 to 4 inclusive, a manganese steel wear liner 2 is attached to the cast iron or steel buffer head 1. The buffer head is carried on guides 7 which form an integral part of the tender drag box casting. The guides 7 and the contact surfaces on the cast iron or steel buffer 1 are fitted with wear liners 6. The wear liners 6 of the guides 7 are made of a suitably selected material such as manganese steel or bronze. The radiused surface of the buffer head 1 is forced by means of springs of suitable strength 3 against a case hardened steel rubbing block 4 which is located on the engine drag box. The steel rubbing block is provided with lubrication grooves 5a and pipe connections 5 through which a suitable lubricating material can be applied so as to reduce the friction and wear on the contacting surfaces of the buffer head 1 and the rubbing block 4.

To remove the interdrawbar 10 it is necessary to relieve the spring load between the buffer head 1 and the rubbing block 4. This is arranged by means of four stud assemblies 9, each including a stud, a castellated nut and a cotter pin, the nuts being so located that the buffer head 1 has freedom of movement over the sharpest curve in the track. Whenever it is required to remove the drawbar pins, one of which is shown at 11 in Figure 1, the cotter pins are removed and the castellated nuts are screwed down so as to compress the buffer springs 3, which action automatically relieves the load on the rubbing block 4 and the resultant tension in the interdrawbar 10. The drawbar pins can then be removed without any difficulty. When coupling up, the drawbar pins are first inserted and the castellated nuts of the assemblies 9 are screwed back so that there is adequate clearance for self-aligning of the head on the sharpest curve of the track and the cotter pins are inserted into the studs to prevent the castellated nuts of the assemblies 9 from altering their position under the action of locomotive vibration.

The cast iron or steel radiused buffer head 1 and the rubbing block 4 are designed to provide an ample bearing area to take the designed spring load, without causing excessive wear.

Additional lubrication points 8 are provided on the guides 7 in the tender front drag casting so as to reduce friction and minimize wear.

If reference is made to Figures 5 to 10 inclusive, it will be appreciated that the construction there shown differs from the arrangement of Figures 1 to 4 inclusive, primarily in the number and location of the springs which bias the buffer head on the tender toward the engine rubbing block.

In Figures 5 to 10 inclusive, the buffer head is designated by numeral 21 and the rubbing block by the numeral 24. The manganese steel wear liner on the radiused surface of the buffer head 21 is designated by numeral 22. Lubricants are supplied to the face of the rubbing block 24 through conduits 25 and internal channels 25b, the latter terminating in ports 25a in the face of the rubbing block.

As is the case with the apparatus of Figures 1 to 4 inclusive, the buffer head 21 is carried on guides forming an integral part of the tender

drag box casting. These guides bear reference numeral 27 and are provided with wear liners 26, see Figure 8. Note also that the guides 27 are provided with fittings 28 for the application of suitable lubricants thereto.

While in Figures 8 and 9 the details of the guides 27 and the wear liners 26 are shown, it is to be understood that the guides 7 are fashioned in the same way and that in materials of construction and assembly the liners 6 and 26 are in correspondence.

A group of four nut, bolt and cotter pin assemblies 29 hold the buffer plate 21 to the tender drag box assembly. These assemblies correspond in structure and function to the assemblies 9 described in connection with Figures 1 to 4 inclusive. The springs 23, however, which appear in Figures 5 to 10 inclusive, are different in number and arrangement from the springs 3 of Figures 1 to 4 inclusive, for, in Figures 1 to 4 inclusive, there are four springs 3 arranged symmetrically about the interdrawbar axis equal radial distances therefrom, while, in Figures 5 to 10 inclusive, there are only two springs 23, also symmetrically arranged and equidistant from the long axis of the interdrawbar, albeit differently positioned.

The following important constructional features of the present invention should be carefully borne in mind:

(1) The aperture through which the interdrawbar passes has to be sufficiently large to admit of the maximum inclination of the drawbar under the worst conditions of engine and tender wear without fouling.

(2) It is necessary to determine the clearance required between the buffer head 1 and the tender drag box casting to ensure that the buffer head aligns itself as a floating head without bearing on the drag box casting except at the two guides specially provided.

(3) The clearance between the tender guides and the buffer head has to be so designed as to give a negligible movement in the vertical direction and a lateral play of not more than $\frac{1}{8}$ " for effective guiding.

(4) Sufficient clearance will have to be allowed between the studs and the stud holes provided in the buffer head to permit the self-alignment of the latter.

It may be noted that the wear liners on the buffer heads are shown as made of manganese steel by way of illustration only. They can be made of any hard wearing metal. Further, the materials of all surfaces in contact and subject to wear are specially selected so as to minimize this wear.

Generally the invention provides for the efficient control of all shuttling forces and torque variations, requires a minimum of maintenance, and functions in a way that the effects of the forces are distributed over the total mass of the tender and the engine, reducing thereby the possibility of longitudinal vibrations to the very minimum.

While this invention has been described with regard to an engine and tender articulation, it is to be understood that it is equally acceptable for use with other articulated units.

What is claimed is:

A buffering assembly for the connection of articulated railway units comprising a rubbing block on one of said units, a drag sill on the other of said units, said drag sill, including integral lugs, a buffer head mounted on said lugs for

free forward and backward movement but restricted against movement in the vertical direction, a drawbar connecting said units, said buffer head and rubbing block having central apertures for the reception of the drawbar so that the buffer head and drawbar are concentric and the buffing surface of the buffer head is symmetrically distributed around the drawbar, a plurality of springs biasing said buffer head away from said drag sill and against said rubbing block, 10 said springs being symmetrically arranged about the drawbar axis and means for the lubrication of the contact surfaces between the buffer head and the rubbing block so as to reduce lateral frictional forces and keep the wear on the surfaces to a minimum, said means comprising lu-

bricant-fed channels in said rubbing block opening to the contact surface of said block.
